UNITED STATES PATENT OFFICE

110,169

DESIGN FOR A DRESS

Morris Bloom, New York, N. Y.

Application May 20, 1938, Serial No. 77,295

Term of patent 3½ years

To all whom it may concern:

Be it known that I, Morris Bloom, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The design is characterized by the combination on the dress disclosed, of the particular embroidery, arranged on the front and rear portions of the dress as shown.

I claim:

The ornamental design for a dress, substantially as shown, and described.

MORRIS BLOOM.
